UNITED STATES PATENT OFFICE.

HENRY L. LEWEN, OF SAN FRANCISCO, CALIFORNIA.

REINFORCED CONCRETE CONSTRUCTION.

995,069.

Specification of Letters Patent. Patented June 13, 1911.

Application filed July 13, 1910. Serial No. 571,743.

To all whom it may concern:

Be it known that I, HENRY L. LEWEN, a citizen of the United States, residing in the city and county of San Francisco and State 5 of California, have invented new and useful Improvements in Reinforced Concrete Construction, of which the following is a specification.

This invention relates to a reinforced concrete construction for use in the erection of fire-proof and earthquake-proof buildings, and pertains especially to a reinforcing element and concrete slab for constructing hollow walls, partitions, floors, ceilings, roofs, 15 etc.

The object of this invention is to provide a reinforcing element and reinforced concrete slab, which is especially applicable for use in the construction of hollow walls and 20 partitions in buildings which are liable to be subjected to shock, as in earthquakes and tremblings of the ground; which can be made up at the factory and shipped complete to be erected into the building, doing 25 away with the use of all wood, either for molds or other purposes.

A further object is to provide a concrete slab, which, while being capable of sustaining great loads and resisting torsional 30 strains, will permit of a certain lateral bending movement when subjected to shock or vibration.

Another object is to provide a reinforced concrete slab which may be readily assembled 35 in a wall or partition and easily removed therefrom, and which is simple in construction and economical in manufacture.

The invention consists of the parts and the construction and combination of parts 40 as hereinafter more fully described and claimed, having reference to the accompanying drawings, in which—

Figure 1 is an elevation of my invention with parts broken away, showing the reinforcements. Fig. 2 is a cross section on the line $x-x$, Fig. 1, showing the slabs as assembled to form a hollow wall. Fig. 3 is a detail in section showing a yielding corrugation or hollow rib formed on the reinforcing plate. Fig. 4 is a modified form of the corrugation or rib. Fig. 5 is a perspective view showing the invention as applied in building construction to walls and roofs.

As a foundation or base for my slab, and 55 as a building element *per se* of novel design and utility, I employ a sheet-metal strip A,

of suitable size, weight and length. I prefer to use thin sheet-metal, such as is employed ordinarily in making metal lath or the like, and which strip or sheet, before shaped in 60 the manner herein described, possesses little inherent rigidity. The sheet may be two feet, more or less in width, and ten or twelve feet, more or less, in length; generally its length is determined by the height of the 65 wall or partition into which it is to be installed. The sheet is generally flat and imperforate, except as hereinafter described. The sheet is rolled or otherwise formed with longitudinal corrugations or hollow ribs 2, 70 and the side edges are bent to one side at right angles, as shown at 3, and oppositely to the ribs 2, and are then outwardly bent, as at 4, parallel with the body of the strip to form fastening flanges and strengthening 75 webs, as later described. These ribs 2 are spaced at regular intervals, preferably about six inches, more or less, apart, on the side of the plate opposite flanges 3 and 4, and project outwardly therefrom a distance proportional 80 to the thickness of the finished slab. They are shaped in section, preferably as shown in Fig. 3, the sheet metal being bowed outwardly in the form of a U, and slightly contracted near the juncture with the plate 85 A so as to provide a rib capable of yielding slightly to compressions transversely of the plate, and also permitting the plate to bend slightly, and avoiding surfaces which would tend to crack the cement or concrete where 90 the latter is thinnest, at point 5, Fig. 2, when subject to expansion and contraction by heat, cold or seismic disturbances. The ribs 2 are perforated transversely at intervals throughout their length, as shown at 6, in Fig. 3, 95 usually about six inches apart, to admit of the insertion of reinforcing rods 7, which are laced in and out, through one rib and over another, in alternate fashion throughout the length of each plate A, and all the connected plates, as shown in Figs. 1, 2 and 5. The outer ends of the truss rods 7 extend beyond the outermost ribs of a plate and may be split or forked, or otherwise headed, as shown at 8, to provide an anchor in the 100 grouting which fills the space 9 between the adjacent flanges 3 of two adjoining plates. If desired, the alternate rows of rods 7 may be woven through the alternate ribs 2, as shown in dotted lines, Fig. 2. The flanges 105 3 generally extend a distance equal to half the width or thickness of the desired wall or

- partition; and the flanges 4 are perforated at suitable intervals to receive bolts 10 when the finished slabs are set in position, as later described.
- 6 In addition to the reinforcing rods 7, I may employ the diagonally arranged brace wires 11, and interlace them across the face of the plate A, the wires 11 being preferably wrapped around each reinforcing rod 7, as shown in Fig. 1. The diagonal wires 11 strengthen the finished slab against diagonal strains, the transverse reinforcing rods 7 resisting lateral strain and the vertical ribs 2 resisting vertical strain.
- 15 After the reinforcing rods 7 and diagonal wires 11 are in place, the face of the plate A is covered with concrete, cement, or other suitable plastic material 12 to the required depth, it being understood that the present invention contemplates that, as a general rule the plate is coated while lying in a horizontal position, and before being assembled into the building; the finished slab constituting a building element made up of the 20 plate A, or its equivalent, the rods 7, wires 11 and plastic material 12. Manifestly, however, it is possible that I may omit the wires 11 and might also omit the rods 7, and that the corrugated plates A, with or without 25 their rods 7 or wires 11 might be erected in place in a building and plastered over later with the plastic material 12. The plastic material 12 covers the face of the plate A between the outermost ribs 2, and when 30 sufficiently hardened the whole forms a portable reinforced concrete or cement slab which can be readily transported and set up and assembled in a small wall or partition, as will now be described. The slabs are prefer- 35 ably made in the required lengths for a wall or partition of a given height, but they can be sawed or cut to any length, as required. They are stood up on end in a channel shoe or guide groove 13, Fig. 5, securely 40 fastened to a foundation or other support 14.
- For each wall section two slabs are placed back to back, with their flanges 4 overlapping, and the next pair of slabs have their flanges 4 overlapping or interleaving with 45 the first pair, and so on, as in Fig. 2; each bolt 10 passing through four flanges 4, so that each pair of slabs is connected by a narrow stiff vertical metal web across each space 9 in the plane of the wall. The bolts 10 are 50 inserted through the connecting flanges 4 at suitable intervals, thus binding the adjacent outer and inner slabs together and forming a hollow wall with the flue spaces 15 for ventilation, water pipes, electric wires, etc.
- 55 This is continued until a wall of the required length is constructed. The space 9 between the adjacent pairs of slabs may be filled with concrete by placing a plank 16 in vertical position to form a mold and filling in at the 60 top. This space 9 may also be utilized for
- conducts 18 of any description, and where columns are needed may be studded with vertical rods 17 to form a substantial support for girders or the like. The flues 15 between each pair of outer and inner slabs, 70 besides being utilized for ventilating purposes, form a dead air insulation against heat and cold and sound. The slabs may also be employed in floor and roof construction, see Fig. 5, being sufficiently strong 75 where properly supported to sustain tremendous weight.
- From the foregoing it will be seen that the slabs form a finished product before setting into a wall, therefore not requiring 80 specially skilled labor in the construction of a building.
- The concrete being comparatively thin over the face of the longitudinal ribs 2, will admit of a limited flexible movement of the 85 plate A, when subjected to a violent shock without damaging the outer face of the wall, the reinforcing bars 7 and diagonal wires 11 preventing the concrete from being shaken off the back plate A. The wires 11 90 may be spaced at any suitable intervals and may be disposed vertically, as well as diagonally, if desired. The ribs or corrugations 2 and the hollow construction of Fig. 2 render the wall extremely strong on compres- 95 sion. The individual plates A, with their corrugations 2, form a very important feature in this invention, as the ribs may be differently shaped, if desired; the form illustrated in Fig. 4 being occasionally employed. 100
- It is manifest or possible that the construction herein specified may be varied without departing from the principle of the invention, and I desire it to be understood that the invention is not limited to any 105 specific form or arrangement of parts, except in so far as such limitations or their mechanical equivalents are specified in the claims.
- Having thus described my invention, what 110 I claim and desire to secure by Letters-Pat- ent, is—
1. A building element consisting of a thin metal sheet formed with lengthwise extending hollow ribs at intervals, said ribs being substantially U-shaped in cross section with the legs of the U where it joins the body of the sheet drawn in and contracted to form a comparatively narrow opening into the hollow of the rib, said ribs adjacent to their juncture with the body of the sheet being transversely perforated, and truss wires laced through the perforations of alternate 115 ribs and over an intermediate rib.
  2. A building element comprising a strip 120 of sheet metal with projecting ribs running lengthwise of the strip, said ribs being perforated, and truss wires laced through the perforations in one rib and over a succeed- 125 ing rib.

3. A building element comprising a metal strip with lengthwise extending springy ribs projecting from one side of the strip, the ends of the strip being oppositely bent to 5 form flanges, a second similar strip placed back to back therewith, the two strips secured together on their overlapping flanges and inclosing a hollow space, said strips having their ribs perforated, and truss rods 10 woven through the perforations in alternate ribs and over the intermediate ribs.
4. A building element consisting of a sheet metal strip having longitudinally extending springy partially closed ribs, said ribs perforated, and truss rods woven through the 15 perforations of certain of said ribs and passing over other ribs.
5. A building element consisting of a sheet metal strip having longitudinally extending, springy, partially closed ribs, said ribs being perforated, truss rods woven through 20 said perforations, and diagonal brace wires secured to the truss rods.
6. A building element consisting of a sheet metal strip having longitudinally extending 25 springy, partially closed ribs, said ribs being perforated, truss rods woven through said perforations, diagonal brace wires secured to the truss rods, and a second and similar 30 trussed and stayed ribbed strip, with the two strips placed back to back to inclose a hollow flue space.
7. A building element consisting of a sheet metal strip having longitudinally extending 35 springy, partially closed ribs, said ribs being perforated, truss rods woven through the perforations, diagonal braced wires secured to the truss rods, a second and similar
- trussed and stayed ribbed strip with the two strips united back to back to form two opposite walls of a hollow flue space, said strips having lateral flanges forming two remaining opposite walls of the flue space, and a similar pair of united strips connected to the first pair. 40
8. A building element consisting of a sheet metal strip with longitudinally extending perforated ribs, trussed rods woven through the perforations of certain of the ribs and passing outside of intermediate ribs, said 45 rods having a length in excess of the width of the ribbed portion of the strip and provided with expanded heads.
9. A building element consisting of a sheet metal strip with longitudinally extending 50 perforated ribs, trussed rods woven through the perforations of certain of the ribs and passing outside of intermediate ribs, said rods having a length in excess of the width 55 of the ribbed portion of the strip and provided with expanded heads, said ribs and rods embedded in concrete to form a slab.
10. A building element, consisting of a metal plate having lengthwise extending ribs on one side and lateral angular flanges 60 projecting from the other side, said ribs perforated, and truss rods extending transversely of the plate and interlaced over and through alternate of the ribs.
- In testimony whereof I have hereunto set 65 my hand in the presence of two subscribing witnesses.
